UNITED STATES PATENT OFFICE.

FRANK IPPOLITI, OF PHILADELPHIA, PENNSYLVANIA.

GARMENT POCKET.

Application filed November 14, 1924. Serial No. 749,835.

To all whom it may concern:

Be it known that I, FRANK IPPOLITI, a citizen of the United States, residing at Philadelphia, in the county of Philadelphia and State of Pennsylvania, have invented certain new and useful Improvements in Garment Pockets, of which the following is a specification.

My invention relates to garment pockets, 10 and more particularly to those known as patch pockets.

The objects are to stitch the pocket sections so that the pocket will not have an objectionable raw edge therein, or an unsightly welt around the edge outside of the pocket.

These objects, and other advantageous ends which will be described hereinafter, I attain in the following manner, reference 20 being had to the accompanying drawing in which—

Figure 1 is a face view of a garment section having my improved pocket stitched thereto,

25 Figure 2 an enlarged section on line 2—2 of Figure 1, and

Figure 3 an enlarged fragmentary section of the stitching shown in Figure 2.

Referring to the drawings, 1 indicates a 30 garment section, 2 a pocket section stitched from its inner side 3 to the garment section by stitching 4 adjacent the edge thus providing an inwardly turned flap as shown, and 5 a lining stitched from its outer side 6 to the inner side of said flap by stitching 8 thus forming an outwardly turned flap on 35 said lining secured to the inwardly turned flap on the pocket section. The side edges and bottom edges 9 of the pocket are 40 stitched as above described. The upper

open edge of the pocket may be sewed in the ordinary way. A flap 11 may be sewed to the garment section in any suitable manner.

A pocket stitched as above set forth does 45 not have the objectionable raw edges of the pocket section and lining therein, or an unsightly welt around the side and bottom edges 9.

While I have described my invention as 50 taking a particular form, it will be understood that the various parts may be changed without departing from the spirit thereof, and hence I do not limit myself to the precise construction set forth, but consider 55 that I am at liberty to make such changes and alterations as fairly come within the scope of the appended claims.

Having thus described my invention, what I claim as new and desire to secure by 60 Letters Patent is:—

1. In combination with a garment section, an outer pocket section stitched adjacent to its edges to said garment section, the edges of said pocket section being turned 65 inwardly to form an inwardly turned flap; and a lining stitched to the side of said flap adjacent the garment section.

2. In combination with a garment section, an outer pocket section stitched from 70 its inner side a short distance from its raw edge to the garment section, thus forming an inwardly turned flap; and a lining provided with an outwardly turned flap stitched to the inner side of the inwardly 75 turned flap on the pocket section.

In testimony whereof I have signed my name to this specification.

FRANK IPPOLITI.
